DESIGN FOR A TEXTILE FABRIC

Annie Wolff Noy, Brooklyn, N. Y., assignor to
Bates Manufacturing Company, Lewiston,
Maine, a corporation of Maine

Application December 30, 1938, Serial No. 82,080

Term of patent 14 years

To all whom it may concern:

Be it known that I, Annie Wolff Noy, a citizen of Germany, residing at Brooklyn, in the county of Kings, State of New York, U. S. A., have invented a new, original, and ornamental Design for a Textile Fabric, of which the following is a specification, reference being had to the accompanying drawing, forming part thereof,

In the drawing, Fig. 1 is a plan view of a piece of fabric showing my new design; and Fig. 2 is a cross-section on the line 2—2 of Fig. 1.

I claim:

The ornamental design for a textile fabric, substantially as shown.

ANNIE WOLFF NOY.
